CALVIN WARDWELL, OF PAINESVILLE, OHIO, ASSIGNOR TO HIMSELF AND H. H. COE, OF SAME PLACE.

Letters Patent No. 89,097, dated April 20, 1869.

IMPROVEMENT IN AUGERS.

The Schedule referred to in these Letters Patent and making part of the same.

To all whom it may concern:

Be it known that I, CALVIN WARDWELL, of Painesville, in the county of Lake, and State of Ohio, have invented certain new and useful Improvements in Slip-Spike and Bung-Bit; and I do hereby declare that the following is a full and complete description of the same, reference being had to the accompanying drawings, making a part of this specification, in which—

Figure 1 is a side view of the bit.

Figure 2 is an end view.

Like letters refer to like parts.

My invention consists in the construction of a boring-bit, having a capacity for boring with one operation a hole for the body of a spike, and an enlarged hole for a bung or plug over the head of the spike.

In spiking the outside plank to the sides of a ship, it is customary to bore a hole for the admission of the spike, which being done, a section of the hole is then enlarged for the admission of the head of the spike, which is sunk to a considerable distance in the timber or plank.

The hole is then plugged up with a bung, thereby keeping the spike from immediate contact with the water.

The usual method of boring said holes is by the employment of the separate augers or bits of the proper size, boring first with a large auger to the proper depth for the spike-head, after which following with a smaller one for the spike, thus making two separate operations, requiring much time to perform, in consequence of the time required to change the bits; also, without the exercise of much care, the holes are not bored true in their relation to each other. Hence the head of the spike will sometimes lean to one side, and in driving it in will crowd against and tear the sides of the hole, so that the bung will not fit well and tight.

To avoid this trouble and defect, consequent of the use of two separate bits, I construct the auger as shown in the drawing, fig. 1, in which A is the section for boring for the spike, which is of the proper length and size.

B, the upper section, is for the bung, of the proper length and size; the two, as will be seen, comprising but one bit.

The cutting-edge and twist of the auger are the

same as those in ordinary use, as shown in fig. 2, and the practical use of the same is as follows:

The spike-section of the auger is first bored into the wood, which is followed by the enlarged section B, for the bung, thereby cutting the two holes at one operation, and in true relation to each other.

By the use of this implement, the work is done in much less time and with less expense, as one auger only is required for the work. Hence, no time is spent in changing bits, and, as above said, the bung-hole being in true relation with the spike-hole, the head of the spike will at all times enter free from crowding, so that the hole in consequence is true and smooth for the admission of the bung.

I am aware that implements have been used in which there was a boring-bit that would bore a hole for the body of a spike, and such bit was detachable from another part that bored a larger hole, such having been patented January 7, 1868.

The construction and operation of the implement therein described and claimed, have no analogy to what I claim as my invention, for, while the patented implement will bore, to a limited extent, the two-sized holes, yet it cannot do it so well as mine; because the cutters that bore the larger hole are not calculated to cut when the other or smaller bit is doing its work. Nor is there any provision in the implement for discharging the chips out from the enlarged hole, the tool being for an entirely different purpose from what mine is used for.

I am also aware that many different devices are used with boring-bits, which may be adjusted upon said bit, that will bore an enlarged hole. Such bit I do not claim, as mine is made in one tool, and is not susceptible of change, and is to be used as any ordinary bit.

Having thus described my invention,

What I claim as my improvement, and desire to secure by Letters Patent, is—

A boring-bit, having the small part A and large part B, constructed together in one and the same tool, to operate in the manner and for the purpose described.

CALVIN WARDWELL.
